Chemiglas, Inc., San Diego, Calif., a corporation of California

Application April 15, 1954, Serial No. 30,033

Term of patent 14 years

(Cl. D21—6)

To all whom it may concern:

Be it known that I, William D. O'Morrow, a citizen of the United States, and a resident of the city of La Jolla, County of San Diego, State of California, have invented a new, original, and ornamental Design for an Awning or Similar Article, of which the following is a specification, reference being had to the accompanying drawing, forming a part thereof.

The awning top member and other bracket have been omitted in Figures 3 and 4 for convenience of illustration.

The broken line fragmentary showing of a door frame is for illustrative purposes only.

The dominant features of my new design are shown in solid lines in the drawing.

I claim:

The ornamental design for an awning or similar article, as shown and described.
